United States Patent

Des. 238,776
Patented Feb. 10, 1976

238,776

GRATING

Ronald McKenzie Howells, Yennora, New South Wales,
Australia, assignor to Comalco (J & S) Pty. Limited

Filed Nov. 6, 1972, Ser. No. 304,107

Claims priority, application Australia June 8, 1972

Term of patent 14 years

Int. Cl. D25—02

U.S. Cl. D13—1 J

FIG. 3

FIG. 1

FIG. 1 is a perspective view showing portion of a grating which is of indefinite length and of indefinite width;

FIG. 2 is a plan view of said portion of a grating; and

FIG. 3 is a section taken on line 3—3 of FIG. 2.

I claim:

The ornamental design for a grating, as shown and described.
